United States Patent Office

Des. 208,682
Patented Sept. 19, 1967

208,682

COMB

James E. Tucker, Chicago, Ill., assignor to The Gillette Company, Boston, Mass., a corporation of Delaware

Filed Nov. 28, 1966, Ser. No. 4,813

Term of patent 14 years

(Cl. D86—8)

FIG. 1

FIG. 2

FIG. 3

FIG. 4

FIG. 5

FIG. 1 is a view in side elevation of a comb showing my new design;

FIG. 2 is a top plan view;

FIG. 3 is a view in end elevation taken from the left hand end of FIG. 1;

FIG. 4 is a sectional view taken along line 4—4 of FIG. 2; and

FIG. 5 is a sectional view taken along line 5—5 of FIG. 2.

I claim:

The ornamental design for comb, as shown.
